[57] **ABSTRACT**

The invention relates to a damping and control device for a bogie bolster allowing relative movements between side-frames and bolster, said movements being however controlled and damped so as to return to an equilibrium position.

DAMPING AND CONTROL DEVICE FOR A BOGIE BOLSTER

This invention relates to bogies of the type in which the structure comprises three main parts, namely a bolster and two side-frames in cast steel or manufactured by any other process.

The essential object of the invention is to provide such structure in which all the relative movements between the side-frames and the bolster are not only allowed, but also duly controlled, damped and, additionally, systematically returned to the equilibrium position.

Another object of this invention is to provide such structure in which the safety conditions are fully met, even should one of the moving parts of the structure be lost.

Said device is characterized in that each end of the bolster engages a housing formed by one side-frame, rests upon resilient members, and is laterally interfitting on both sides with the adjoining portion of the side-frames and, on one side, rests directly upon the side-frames and, on the other side, rests upon the side-frame through the intermediary of a resiliently loaded moving insert.

The said interfittings are provided by re-entering or projecting portion of the bolster and the side walls defining the housings in the side-frames of the bolster ends.

Said re-entering and projecting portions are advantageously defined by vertical walls.

The cross-section of the said re-entering and projecting portions will be generally V-shaped.

In a preferred embodiment, the re-entering portions will be provided by the bolster and the projecting portions by the side-frames. Of course, the moving insert will be determined in its shape, sizes and relative position in accordance with the local characteristics of the bolster and the side-frames. Generally, said insert will function as a wedge and it will be profiled to partially engage a window provided in the adjoining wall of the side frames. When mounting, said insert will be secured between the bolster and the side-frame, but it will be released after mounting to be permanently subjected to the actuations of a resilient number provided therefor.

In order to provide better stability, the moving inserts will be diagonally disposed within the same bolster.

Of course, it will be possible to carry out said essential features in very varying embodiments and they will be completed by any disposition, configuration and particular arrangements in accordance with the embodiments being made.

A preferred embodiment will be described hereafter without any limitation, reference being made to the attached drawings in which:

FIG. 1 shows a vertical section of the essential elements of a bogie using the device of this invention;

FIG. 2 is a plane view thereof;

FIG. 3 shows, on an enlarged scale, the portion indicated in F3 on FIG. 2;

FIG. 4 shows a section on the line IV—IV of FIG. 3;

FIG. 5 shows, on an enlarged scale, the portion indicated in F5 on FIG. 4;

FIG. 6 is similar to FIG. 5 during a mounting or dismantling step.

Each end of bolster 1 is introduced into a housing 2 provided on the side-frames 3. The latter rest upon the bottom of the said housings through intermediary of coil springs 4. At both ends and on each of its side faces, the bolster has a V-shaped re-entering portion 5-6 respectively with vertical sides on which wear plates 7-8 and 9-10 respectively are secured, e.g., by welding. The housings 2 of the side-frames have V-shaped projecting side faces 11-12 respectively with vertical sides, the face 11 being also provided with welded wear plates 13-14 respectively.

The side face 12 is traversed by a central opening 15 the upper portion of which is extended rearwards of the V-section by an inclined flat wall 16 which, inside the angle, is traversed by a hole 17. Rearwards and in the axis of the said opening 15, the side-frame has a seating surface 18 for a spring 19. On the other hand, the latter rests on a wedge 20 the general shape of

which is similar to that of a V-folded plate having a constant thickness with, inside the dihedron, a projection 21 the upper face 22 of which functions as a guide in cooperation with said inclined wall 16 of the side-frame. This wedge forms the moving insert between the bolster and the side-frames. It is perforated with holes 23-24 respectively provided in the upper and lower walls of its projecting portion, said both holes being in alignment at least through one of their generatrices, it being possible to secure them in front of the hole 17 provided in said rear inclined wall 16 of the side-frame when the said wedge 20 is pushed home in the side-frame against the spring 19.

The damping and control device being so realized, it results that, on the stationary side 5, the bolster 1 is directly contacting the side-frame through its wear plates 7-8. On the other side 6, the bolster is contacting the wedge 20 the projection of which is introduced into the opening 15 provided in the V-section of the side-frame while sliding on the lower guiding face of the inclined wall 16 of the side-frame. Under the action of the spring 19, the wedge 20 is pressed into the V-section of the bolster and it repels the whole assembly thereof towards the opposite side, i.e., on the wear plates 13-14 of the side-frame.

For mounting the device, the spring 19 will be merely slid through the opening 15 of the V-section of the side-frame by contacting it with the stationary seat 18 integral with said side-frame. The wedge 20 is located by driving it, e.g., by means of a press. When the wedge is fully driven, the openings 23-24 thereof are in front of the opening 17 of the side-frame. It is then sufficient to introduce a rod 25 into the aligned openings

17-23-24, thereby momentarily blocking the wedge 20 in the re-entered position. The bolster 1 is then merely slid in the correct position from the top of the side-frames and, finally, the rod 25 is removed by pulling it axially, thereby releasing the wedge 20 through which the bolster is kept into position.

With this arrangement, the vertical shiftings of the bolster give rise to a dry friction, on one hand, between the wear plates of the side-frame and the bolster and, on the other hand, between the wear plates of the bolster 1 and wedge 20.

These friction effects are a function of the spring pressure.

It should be noted that, owing to the inclined position of the guiding face 22 of wedge 20, the upward movement of bolster 1 is additionally damped owing to the developed wedge effect.

It will be also observed that the transverse oscillations are not pure and are accompanied with a slight longitudinal shifting since one of the sides of the V-section of the bolster slides upon a side of the stationary V-section of the side-frame. Thus, the lateral shifting of the bolster at that location will only occur in a parallel direction with said contacting faces. The magnitude of said movements is limited to the clearance remaining between the wedges and the side-frame.

It should be noted that said lateral movements are dry damped owing to the friction between the wear plates, while being also subjected to a return force produced by the action of spring 19 tending to repel the bolster 1 and to interfit the wear plates 7-8 of the V-section of the bolster with the wear plates 13-14 of the V-section of the side-frame.

On the other hand, since the bogie consists of two identical side-frames 3, when considering the longitudinal shifting, i.e., the direction of the rails, of bolster 1 in a given direction, said shifting is prevented on one side of the bolster owing to the bearing upon the stationary V-section of the side-frame, whereas the wedge 20 sinks at the level of the other side-frame.

Consequently, said movement is not pure for the assembly of the bolster. In fact, it is a slight pivoting movement of the bolster about the stationary V-section of any of the side-frames according to the pivoting direction and the magnitude of the shifting at the level of the center of the bolster or the center-casting is equal to the half clearance between wedge and side-frame. This movement is accompanied with a slight damping, since, when sinking, the wedge tends to fall down because it slides along the inclined wall 16 of the side-frame. The cooperation of spring 19 generates the return force necessary for bringing the bolster in its rest position, i.e., into contact with the stationary V-section of the side-frame.

The V-sections 11 of the side-frames 3 and the V-sections 5 and 6 of the bolster being protected against wear by plates 13, 14 and 7,8,9,10 of hard steel or any other suitable material, the wedge 20 contacting plates 9 and 10 with its vertical surfaces must be also made of a wear resistant material. A suitable material therefor could be steel treated for a high hardness.

It is apparent that this embodiment and, more particularly, the different constituting parts is only given by way of example and may be modified or replaced by any other element having an equivalent shape or function.

The invention relates as well to the device as a novel mechanical combination as an Y of the characteristical constituting parts intended for making said mechanical combination.

What I claim is:

1. In a railway truck, a bolster having opposed ends, each of said ends having two opposed lateral vertical walls, each of said walls being V-shaped in horizontal cross-section, two op-

posed side frames, each of said side frames having two opposed lateral vertical walls, each of the last-mentioned lateral walls being V-shaped in horizontal cross-section, said side frames having openings receiving the ends of said bolster, 5 whereby some of the first-mentioned lateral walls are engaged by some of the last-mentioned lateral walls, a guide wall engaging one of the last-mentioned lateral walls, said guide wall being located adjacent an opening formed in said one last-mentioned lateral wall and being inclined downwardly and outwardly relatively to said opening, a wedge having a vertical wall which is V-shaped in horizontal cross-section and is located between one of the first-mentioned lateral wall and said one last-mentioned lateral walls, said wedge also having an inclined wall engaging said guide wall, and a spring engaging 10 said wedge and pressing it against said one first-mentioned lateral wall, said wedge having rod-engageable openings, whereby the wedge may be maintained momentarily in a retracted position.
